Patented Oct. 16, 1917.

UNITED STATES PATENT OFFICE.

GEORGE THOMAS IRWIN, OF TORONTO, ONTARIO, CANADA.

STANDARD ELECTRIC LAMP.

1,243,675.

Specification of Letters Patent.

Patented Oct. 16, 1917.

Application filed November 6, 1916. Serial No. 129,823.

To all whom it may concern:

Be it known that I, GEORGE THOMAS IRWIN, of the city of Toronto, in the county of York, in the Province of Ontario, Canada, have invented certain new and useful Improvements in Standard Electric Lamps, of which the following is the specification.

My invention relates to improvements in standard electric lamps and the object of 10 the invention is to devise means whereby a lamp bulb and shade may be adjusted to any desired position convenient to the user and such as will be simple and cheap to manufacture and it consists essentially of a standard 15 extending upwardly from a suitable base, a cross arm supported upon the base so as to swing in a horizontal plane on a center located on a line with the longitudinal axis of the standard, a telescopic extension member to the arm, means for suspending the lamp bulb and shade from the extension arm, a counterweight for the lamp, means for controlling the lamp suspension means so as to retain the lamp in any position to 20 25 which it may be adjusted vertically, and means for supporting the lamp and shade on the suspension means so as to be capable of being adjustably swung in a vertical plane as hereinafter more particularly explained by the following specification.

Figure 1, is a general perspective view of my lamp with the main shade removed and the standard intermediately broken away of its length.

Fig. 2, is an enlarged vertical sectional detail through the lamp standard and lamp supporting parts.

Fig. 3, is an enlarged view of the upper portion of the lamp showing the main shade 40 in position.

Fig. 4, is a sectional detail showing the means of adjustably supporting an incandescent light from the flexible suspension means so as to be adjusted in a vertical 45 plane.

Fig. 5, is an enlarged sectional detail of the main casting and adjacent parts employed in the construction shown in Fig. 4.

Fig. 6, is a perspective detail showing the 50 means for pivotally supporting the cross arm and bracing the same.

Fig. 7, is a longitudinal section through the inner end of the cross arm and its pivot support.

Fig. 8, is a cross sectional view on line 55 $x-y$ Fig. 7.

Figs. 9 and 10, are perspective details of the parts for supporting the arm on which the leading-in wire is supported.

Fig. 11, is a sectional detail of the adjustable weight carried by the flexible connecting wire leading to the hanging incandescent lamp.

Fig. 12, is a plan section on line $x'-y'$ Fig. 2.

Fig. 13, is a plan section on line x^2-y^2 Fig. 2.

In the drawings like letters of reference indicate corresponding parts in each figure.

1 indicates the main standard which is 70 supported on a base 2 which comprises the main socket casting 3 into which the lower end of the standard 1 extends, the lower end of such standard being preferably provided with an enlargement 4 fitting into a corresponding enlargement 4' in the casting 3. 5 indicates radially extending inverted U-shaped members extending from the casting 3, the sides of such members depending beneath the lower end of the enlargement 4 of 80 the standard 1. 6, 7, 8 and 9 indicate feet which fit at their inner ends into the radially extending sockets 5 being secured therein by screws 10. The lower face of the inner end of each foot 6, 7, 8 and 9 is provided with a recess 11, the outer edge of 85 which is concentric with the center of the standard. 12 indicates a circular plate fitting into such recess and forming a closure for the lower end of the hollow standard 1. 90

13 indicates an orifice formed in the center of the plate 12. 14 indicates a wooden plug which is driven up into the lower end of the hollow standard and against the lower end of which the plate 12 bears. 15 indicates 95 screws which extend upwardly through the plate 12 into the plug 14. 16 indicates a cap which fits over the upper end of the standard 1 and is provided with a cylindrical upward extension 16*. The upper edge of the 100 portion 16* is provided with a semicircular recess 16*. 17 indicates a cylindrical member surrounding the member 16* and turnably supported thereon, the lower end of the cylindrical portion 17 either bearing directly 105 upon the upper face of the cap 16 or on suitable balls 18 interposed between the lower end of the portion 17 and the top of the cap 16, the lower end of the portion 17 being chamfered off at its inner edge so as to form 110 a runway for the balls. 19 indicates an arm extending radially out from the upper end

of the portion 17, the arm 19 being provided at its outer end with an upwardly extending lug 20. 17* indicates a projection extending from the portion 17 into the recess 16*. By 5 this means the rotary movement of the member 17 is limited. 21 indicates a projection also extending from the upper end of the portion 17 in diametric alinement with the arm 19. 22 and 23 indicate curved arms extending from the upper end of the cylindrical portion 17 and located diametrically opposite each other in a position at right angles to the diametrically extending arm 19. The upper ends of the arms 22 and 23 10 are provided with sleeve bearings 24 and 25 in which are suitably secured tubular members 26 and 27. 28 indicates an inverted U-shaped member provided with sleeve bearings 29 and 30 into which the upper ends of the tubular members 26 and 27 extend, such member being suitably secured therein.

31 indicates a standard extending upwardly from the center of the inverted U-shaped member 28, at the upper end of which is supported a cluster light fixture 32 from which extends a plurality of sockets 33 designed to carry incandescent bulbs 34. 35 indicates a circular plate provided with a depending annular flange 36 which fits 30 into the upper end of the cylindrical member 17. The plate 35 is provided with a central orifice 37 from which extends a radial slot 38. 39 indicate lugs extending upwardly from the plate 35 at each side of the slot 38, and between which is journaled the grooved pulley 40. 41 indicates a tube passing at its lower end through the orifice 13 of the plate 12 and at its upper end through the orifice 37 of the plate 35. The upper 40 end of the tube 41 is preferably provided with an enlargement 42 into which fits a hard rubber nipple 43 (see Fig. 2). The lower end of the tube 41 is provided with a collar or nut or other enlargement 44 secured thereto and fitting against the inner face of the plate 12.

The extreme lower end of the tube 41 is suitably threaded. 45 indicates a nut which is screwed on to the threaded lower end of the tube 41 against the plate 12. It will thus be seen that the tube 41 extends upwardly centrally through the plate 12, plug 14 and centrally through the standard 1 and plate 35. 46 indicates a cylindrical weight 55 fitting within the hollow standard 1 and provided with a central orifice 47 through which the tube 41 freely extends. By this means the weight 46 is held within the standard and centered so as to slide freely 60 vertically. 48 indicates a cross arm. The cross arm 48 comprises an inner tubular member 49 and an outer tubular member 50. 51 indicates a plug which is secured in one end of the cylindrical member 49, such plug 65 being provided with jaws 52 extending to

each side of the lug 20. 53 indicates a stirrup member, the arms of which extend to each outer side of the jaw 52. 54 indicates a pin which extends through the arms of the stirrup 53, arms of the jaws 52 and lug 20 thereby forming a pivot on which the inner end of the tubular member 49 of the arm 48 swings.

55 indicates a guy wire secured at one end to the upper end of the stirrup 53 and at the opposite end to a suitable portion of the inverted U-casting 28 hereinbefore referred to.

It will be readily understood that the tubular member 50 is freely held upon the tubular member 49 so as to slide telescopically longitudinally thereof. 56 indicates a collar which extends around the tubular member 50 in proximity to the plug 51. 57 indicates a hollow cylindrical portion depending from the collar 56. 58 indicates a spring plunger held within the portion 57 so as to bear against the lower peripheral portion of the tubular member 49. 59 indicates an orifice formed in the tubular member 50 diametrically opposite the plunger 58. 60 indicates a ball fitting in the orifice 59 and bearing against the upper peripheral portion of the cylindrical member 49. By means of the ball 60 and plunger 58 free sliding movement is allowed within the cylindrical member 50 of the cylindrical member 49 but at the same time provides sufficient pressure upon the cylindrical member 49 as to prevent any inadvertent slidable movement of the cylindrical member 50 upon the member 49. 61 indicates a lug which extends outwardly from the plate 35 being provided with an orifice 62. 63 indicates a fork provided with a stem 64 extending through the orifice 62 and through an alined orifice formed in the projection 21. The stem 64 is secured in position by a suitable nut 65 screwed on to the lower end of the stem. The center of the fork 63 is provided with a notch 66 for a purpose which will hereinafter appear. 67 indicates a shoe provided with a grooved edge 68. 69 indicates a pulley, the sheaf 70 of which is provided with a stem 71 extending diametrically through the cylindrical member 50 being secured therein by a suitable nut 73. 74 indicates a similar pulley mounted upon the other side of the shoe 67, the sheaf of which is provided with a ring 75 surrounding the cylindrical member 50 and suitably secured thereto. The shoe 67 is secured to a strap 76 which is suitably secured to the cylindrical member 50. 77 indicates a chain which extends up over the pulley 69 longitudinally through the groove 68 beneath the shoe 67 and then over the pulley 74 through the notch 66 and over the pulley 40. The chain 77 passes downwardly from the pulley 40 through the slot 38 in the plate 35 through

the upper end of the cylindrical member 17, cylindrical portion 16* of the cap 16 and through the standard 1 to the weight 46 to which it is suitably secured adjacent to the center tube 41. 78 indicates a swivel member to which the opposite end of the chain 77 is secured, such swivel member being provided with an eye 79 having an inverted V-shaped portion 80 in the lower portion 10 of its interior periphery. 81 indicates a lamp socket of any suitable construction carrying an incandescent bulb 82 and shade 83. 84 indicates a casting comprising a substantially hollow spherical portion 85 from 15 which extends an externally threaded nipple 86 which is screwed into the upper end of the socket 81. 87 indicates a hook member extending from the spherical portion 85 at right angles to the nipple 86, the inner 20 edge of the upper portion of the hook being provided with a serrated portion 88. 89 indicates a strip of band metal forming a lever and provided with an orifice 90 through which the nipple 86 extends thus firmly 25 securing the upper end of the metal band 89 between the spherical portion 85 and the upper end of the lamp socket 81. The band 89 depends downwardly through the open upper end of the lamp shade 83 and through 30 the lamp shade free thereof so as to project at its lower end past the lower edge of the lamp shade and is provided with a counterweight 89*. 91 indicates a chain secured at one end to the extreme end of the hook 35 87 and at the opposite end to the lower end of the metal band strip 89, such lower end being preferably provided with a perforation through which a hook 92 secured to the lower end of the chain 91 is passed 40 thereby detachably securing the lower end of the chain 91 to the band strip 89. The chain 91 as it passes from the hook 87 to the band strip 89 passes through the ring 79 and the links of the chain engage with 45 the inverted V-portion 80 which bites the chain 91 between the links so as to hold the chain in any desired position to which it may be adjusted. 93 indicates a tubular arm provided with a threaded inner end 50 screwed into an orifice 94 formed in the hollow spherical portion 85 of the casting 84. By means of this tubular arm the lead wires 94* of the lamp are conducted into the spherical portion 85 through the nipple 86 55 into the lamp socket 81 to be secured therein in the usual manner. 95 indicates a pulley carried by the inverted U-shape casting 28. 95* indicates a chain passing over the pulley 95. 96 indicates a ring secured to one 60 end of the chain 95 and surrounding the cylindrical member 50. The opposite end of the chain 95 is also provided with a finger ring 97 designed to engage with the hook 98 when the ring 97 is in the lowermost position. 99 indicates a counterweight carried

by the chain 95* serving to counterbalance the weight of the arm 48 and thereby minimize the effort in lifting the same.

100 indicates an electric wire connector of any suitable type to one member of which 70 the lead wire 94* is secured. 101 and 102 indicate wires leading upwardly from the other member of the connector 100 through the tubular members 26 and 27. 103 indicates the main lead wires which pass upwardly through the tube 41 passing through the upper end thereof and outwardly through an opening 104 oblong in shape so as to prevent the insulations of the wire coming in rubbing contact with the side of 75 the opening and thus wearing off the insulations from which point they branch upwardly and also pass through the tubular members 26 and 27. The upper ends of the wires 103 pass through perforations 104 and 80 105 formed in the inverted U-casting 28 and from thence upwardly through the tubular standard 31 to the cluster light fixture 32 or such wire may be carried upward to the cluster in any other direction desired. The 85 wires 101 and 102 are connected to the wire 103 at any suitable point so as to form a circuit passing through the lamp 82. 105* indicates a counterweight for the lamp 82. Such counterweight is supported by a sheaf 90 pulley 106 of insulating material, the sheaf of the pulley comprising two circular members 107 and 108, the member 108 being provided with an internally threaded recess 109 and the member 107 with an externally 95 threaded stem 110 which is threaded into the recess 109 so as to hold the sheaf members 107 and 108 a definite distance apart and on which the pulley member 111 is rotatably mounted. The lower portions of the 100 members 107 and 108 are provided with eyes 112 and 113 from which extends a flexible connection 114 by which the counterweight 105* is suitably supported. The weight 105* bearing upon the wire 94* exerts a downward pull on the portion 93 which exerts a leverage on the lamp preventing it swaying sidewise when tipped to an angle in a vertical plane. 115 indicates a collar rotatably mounted around the cylindrical portion 16*. 115 The collar 115 is provided with a radially extending lug 116 provided with a vertical orifice 117. 118 indicates a hook provided with a vertically extending rectangular lug 119 designed to fit into an orifice 117. 120 120 indicates a rod secured in the hook 118 and extending therefrom in an upwardly curved direction, the upper end of the arm being provided with a crotch 121 serving as a support for the leading-in wires of the lamp 125 when it is desired to hold such wires clear of the ground at a point adjacent to the lamp. 122 indicates an ordinary main lamp shade which is suitably hung upon the top of the cluster fixture 32 by guy wires 133 130

or by any other suitable means found desirable.

Having described the principal parts involved in my invention I will briefly describe the operation of the same.

When it is desired to lower the lamp 82 all that it is necessary to do is to pull upon the socket 81 when the chain 77 will slip longitudinally through the groove 68 of the shoe 67. As soon as the desired position is reached and the lamp released, the weight of the lamp on one end of the chain and the weight of the counterweight 46 upon the opposite end serves to bind the chain in the groove 68 of the shoe 67 and thereby prevent the chain inadvertently slipping.

When it is desired to raise the incandescent light 82 vertically all that it is necessary to do is to grip the socket 81 and lift it upwardly thereby relieving the tension of the chain passing around the shoe 67. The chain so relieved is then drawn inwardly by the weight 46.

It will be readily understood, of course, that the lamp can be turned circumferentially a quarter turn in either direction around the main standard 1 to any desired position, the cylindrical member 17 turning upon the cylindrical member 16.

When it is desired to adjust the lamp 82 in a vertical plane so as to direct the light rays of the lamp more or less in an upward or downward direction all that it is necessary to do is to lift the chain 91 and pass it either in one direction or the other through the ring 79 until the desired position is reached. The chain is then dropped so as to again reengage with the portion 80, such portion 80 being V-shape forming a sharp inclined bend in the chain preventing it slipping either in one direction or the other.

If it is desired that the lamp 81 be in the vertical position as shown in Fig. 1 the hook 87 is passed through the ring 79 so that the portion 80 engages with the serrations 88. The serrations 88 are provided so that this supporting device may be readily adapted to any size of shade as, of course, the larger the shade the more off center the lamp would hang if some lateral adjustment were not provided for. By adjusting the hook 87 laterally through the ring 79 the center of the shade may be brought directly beneath the center of the ring and thereby insure that the lamp is hung in its true vertical position.

When it is desired to use the lamp for ordinary lighting purposes and not as a reading lamp I draw the ring 97 downwardly so as to engage such ring with the hook 98. When in this position the lamp supporting arm 48 is drawn up into the inclined position shown by dotted lines in Fig. 3 thereby carrying the lamp 82 into a position substantially centrally of the shade and cen-

trally beneath the cluster lights 34. In this position the lamp will have the appearance of an ordinary lamp and none of the adjustable mechanism will then appear to an observer.

From this description it will be seen that I have devised a very simple form of lamp which will be easily adjusted to any desired position either vertically, circumferentially in a horizontal plane or circumferentially in a vertical plane so as to direct the light rays in any desired upward and downward direction and at the same time I have provided a lamp, all the operative parts of which may be hidden beneath the ordinary main lamp shade when it is desired to use the lamp for ordinary lighting purposes and not as a reading lamp.

What I claim as my invention is:

1. In an electric lamp, a main standard, an arm extending diametrically of the main standard and supported to turn in a horizontal plane on a center in a line with the axis of the main standard, a telescopic member carried by the arm, lamp suspension means carried by such telescopic member, and a spring pressed friction member carried by the telescopic member and bearing against the arm.

2. In an electric lamp, a main standard, an arm extending diametrically of the main standard and supported to turn in a horizontal plane on a center in a line with the axis of the main standard, a telescopic member carried by the arm, lamp suspension means carried by such telescopic member, a spring pressed friction member carried by the telescopic member and bearing against the arm, and an anti-friction member also carried by the telescopic member and bearing against the arm at a point diametrically opposite to the spring pressed friction member.

3. In an electric lamp, a main standard, a lamp supporting arm extending diametrically of the main standard and turnable in a horizontal plane on a center in a line with the axis of the main standard, a telescopic member supported upon the lamp supporting arm and having an interior diameter greater than the exterior diameter of the lamp supporting arm, an orifice formed in the telescopic member, a bearing ball held within such orifice so that its lower peripheral portion depends into the interior of the telescopic member and against the lamp supporting arm, and a spring pressed friction member located diametrically opposite the bearing ball and carried by the telescopic member.

4. In an electric lamp, a main standard, an arm extending radially from the main standard, a lamp supporting arm extending diametrically of the main standard and pivotally mounted at its outer end on the

5 radial arm, flexible lamp suspension means depending from the outer end of the arm, a standard support extending from the main standard above the arm, a pulley carried thereby, a chain passing over such pulley and supporting the lamp supporting arm at one end and designed to be manually operated at the opposite end.

10 5. In an electric lamp, a main standard, an arm extending radially from the main standard, a lamp supporting arm extending diametrically of the main standard and pivotally mounted at its outer end on the radial arm, flexible lamp suspension means depending from the outer end of the arm, a standard support extending from the main standard above the arm, a pulley carried thereby, a chain passing over such pulley and supporting a lamp supporting arm at one end and designed to be manually operated at the opposite end, and a hook carried by the main standard with which the free end of the depending chain is designed to engage when the lamp supporting arm 20 is raised to its uppermost position.

25 6. In an electric lamp, a main standard, an arm extending radially from the main standard, a lamp supporting arm extending diametrically of the main standard and pivotally mounted at its outer end on the radial arm, flexible lamp suspension means depending from the outer end of the arm, a standard support extending from the main standard above the arm, a pulley carried thereby, a chain passing over such pulley and supporting a lamp supporting arm at one end and designed to be manually operated at the opposite end, and a counterweight for the arm carried by the chain.

30 7. In an electric lamp, a main standard, an arm extending radially from the main standard, a lamp supporting arm extending diametrically of the main standard and pivotally mounted at its outer end on the radial arm, flexible lamp suspension means depending from the outer end of the arm, a standard support extending from the main standard above the arm, a pulley carried thereby, a chain passing over such pulley, a ring carried by the lower end of the chain and extending freely around the lamp supporting arm, and a counterweight carried by the chain on the opposite side of the pulley.

35 8. In an electric lamp, a hollow main cylindrical standard supported on a suitable base, a guide member extending centrally longitudinally of the hollow standard, a lamp supporting arm carried by the upper end of the standard and extending radially thereof, flexible lamp suspension means carried by the lamp supporting arm and adapted to support a lamp at one end and to extend at its opposite end longitudinally 40 through the hollow standard, and a counter-

weight fitting within the hollow standard and through which the guide member freely extends and to which the end of the flexible lamp supporting member is secured.

45 9. In an electric lamp, a main hollow cylindrical standard, a suitable base for the standard, a tube extending centrally longitudinally through the standard, a plate encircling each end of the tube, one plate bearing against the upper end of the standard and the other plate bearing against the lower face of the base, means carried by the standard for suspending a lamp exteriorly of the standard, and a counterweight for such lamp fitting within the standard and 50 through which the central tube freely extends.

55 10. In an electric lamp, a hollow standard adapted to carry lamp suspension means at its upper end, a cylindrical member surrounding the lower end of the standard and having radially inverted U-shape socket portions, radial feet fitting within such socket portions, a cylindrical member extending centrally through the main standard and depending through the lower end thereof, a plate surrounding such depending end and bearing against the inner ends of the radial feet, means for securing the feet within the U-shaped socket portions, and 60 means for drawing the plate surrounding the central cylindrical member upwardly against the inner ends of the feet.

65 11. In an electric lamp, a hollow main standard adapted to carry lamp supporting means at its upper end, a cylindrical member surrounding the lower end of the base and having radially extending inverted U-shaped socket portions, a plug secured within the lower end of the hollow standard 70 and depending from the lower end thereof, radial feet fitting within the inverted U-shaped socket portions and bearing at their inner ends against the plug, and a plate secured to such plug and extending over the inner ends of the radially extending feet, and means for securing the feet within the inverted U-shaped socket portions.

75 12. In an electric lamp, a hollow main standard adapted to carry lamp supporting means at its upper end, a cylindrical member surrounding the lower end of the base and having radially extending inverted U-shaped socket portions, a plug secured within the lower end of the hollow standard and 80 depending from the lower end thereof, radial feet fitting within the inverted U-shaped socket portions and bearing at their inner ends against the plug, a plate secured to such plug and extending over the inner 85 ends of the radially extending feet, means for securing the feet within the inverted U-shaped socket portions, and a cylindrical member extending centrally through the plate and plug, a securing nut screwed on to 90

the lower end of the cylindrical member against the plate, and means for securing the upper end of the cylindrical member in the upper end of the hollow standard.

- 5 13. In an electric lamp, a main standard, an arm extending radially from the upper end of the main standard having an upwardly extending lug at its upper end, a lamp supporting arm pivoted at one end of 10 the lug and extending therefrom diametrically of the main standard, a fork carried by the main standard at the diametrically opposite side to the radial arm and in which the lamp supporting arm rests, and lamp 15 suspension means carried by the outer end of the lamp supporting arm.

14. In an electric lamp, a suspending support for the lamp provided with the usual lamp socket and shade, a lever arm connected to the top of the socket and extending through the interior of the shade, a member extending upwardly from the lamp socket, a chain connected at one end to such member and at the opposite end to the 20 lever arm protruding through the bottom of the shade, and a ring carried by the suspending member through which the chain passes.

25 15. In an electric lamp, a suspending support for the lamp provided with the usual lamp socket and shade, a lever arm connected to the top of the socket and extending through the interior of the shade and carrying a suitable counterweight, a member extending upwardly from the lamp socket, a chain connected at one end to such member and at the opposite end to the lever arm protruding through the bottom of the shade,

and a ring carried by the suspending member through which the chain passes.

40

16. In an electric lamp, a main standard, a lamp supporting arm carried by the main standard extending at right angles thereto, lamp suspension means depending from the cross arm, a lamp socket, a hollow extension 45 to the upper end of the lamp socket, a tubular member extending outwardly from such hollow member and through which the lead wires of the lamp extend and pass in a downwardly looped form to the main standard, a sheaf carried by the loop of the lead wire, and a counter-weight depending from such sheaf.

17. In a lamp of the class described, a central standard member, a sleeve fitting freely 55 on to such standard member, a shoulder formed on such standard member and on which the bottom end of the sleeve bears, an arm having a crotched upper end, and a detachable connection between such arm and the turnable sleeve.

18. In a lamp of the class described, a central standard member, a sleeve fitting freely on to such standard member, a shoulder formed on such standard member and on which the bottom end of the sleeve bears, an arm having a crotched upper end, a hook member forming the lower end of the arm having a flat sided projection, and a lug extending from the turnable sleeve into which 60 the flat sided projection fits.

GEORGE THOMAS IRWIN.
